(57) **CLAIM**

I claim the ornamental design for scarf cuff jeans and shorts, as shown and described.

DESCRIPTION

FIG. 1 is a perspective view of shorts with scarf cuffs, showing my new design;

FIG. 2 is a front elevational view of the shorts of the invention;

FIG. 3 is a rear elevational view of the shorts of the invention;

FIG. 4 is a left-side elevational view of the shorts of the invention;

FIG. 5 is a right-side elevational view of the shorts of the invention;

FIG. 6 is a top plan view of the shorts of the invention;

FIG. 7 is a bottom plan view of the shorts of the invention;

FIG. 8 is a perspective view of jeans with scarf cuffs;

FIG. 9 is a front elevational view of the jeans of the invention;

FIG. 10 is a rear elevational view of the jeans of the invention;

FIG. 11 is a right-side elevational view of the jeans of the invention;

FIG. 12 is a left-side elevational view of the jeans of the invention;

FIG. 13 is a top plan view of the jeans of the invention; and,

FIG. 14 is a bottom plan view of the jeans of the invention. The broken lines showing a pattern on the scarf in the figures are included for the purpose of illustrating the invention in use, and form no part of the claimed design. The remaining broken lines showing stitching in the figures are included for the purpose of illustrating threaded stitches, and are considered part of the claimed design.
